(57) **CLAIM**

The ornamental design for a conduit fitting, as shown and described.

DESCRIPTION

FIG. 1 is an upper perspective view of a conduit fitting showing our new design in accordance with a first embodiment of the present invention;

FIG. 2 is a lower perspective view thereof;
FIG. 3 is a left side elevation view thereof;
FIG. 4 is a right side elevation view thereof;
FIG. 5 is a front elevation view thereof;
FIG. 6 is a rear elevation view thereof;
FIG. 7 is a top view thereof;
FIG. 8 is a bottom view thereof;
FIG. 9 is an upper perspective view of a conduit fitting showing our new design in accordance with a second embodiment of the present invention;
FIG. 10 is a lower perspective view thereof;
FIG. 11 is a left side elevation view thereof;
FIG. 12 is a right side elevation view thereof;
FIG. 13 is a front elevation view thereof;
FIG. 14 is a rear elevation view thereof;
FIG. 15 is a top view thereof;
FIG. 16 is a bottom view thereof;
FIG. 17 is an upper perspective view of a conduit fitting showing our new design in accordance with a third embodiment of the present invention;
FIG. 18 is a lower perspective view thereof;
FIG. 19 is a left side elevation view thereof;
FIG. 20 is a right side elevation view thereof;
FIG. 21 is a rear elevation view thereof;
FIG. 22 is a front elevation view thereof;
FIG. 23 is a top view thereof;
FIG. 24 is a bottom view thereof;
FIG. 25 is an upper perspective view of a conduit fitting showing our new design in accordance with a fourth embodiment of the present invention;
FIG. 26 is a lower perspective view thereof;
FIG. 27 is a right side elevation view thereof;
FIG. 28 is a left side elevation view thereof;
FIG. 29 is a front elevation view thereof;
FIG. 30 is a rear elevation view thereof;
FIG. 31 is a top view thereof;
FIG. 32 is a bottom view thereof;
FIG. 33 is an upper perspective view of a conduit fitting showing our new design in accordance with a fifth embodiment of the present invention;
FIG. 34 is a lower perspective view thereof;
FIG. 35 is a left side elevation view thereof;
FIG. 36 is a right side elevation view thereof;

(Continued)

FIG. 37 is a front elevation view thereof;
 FIG. 38 is a rear elevation view thereof;
 FIG. 39 is a top view thereof;
 FIG. 40 is a bottom view thereof;
 FIG. 41 is an upper perspective view of a conduit fitting showing our new design in accordance with a sixth embodiment of the present invention;
 FIG. 42 is a lower perspective view thereof;
 FIG. 43 is a left side elevation view thereof;
 FIG. 44 is a right side elevation view thereof;
 FIG. 45 is a front elevation view thereof;
 FIG. 46 is a rear elevation view thereof;
 FIG. 47 is a top view thereof;
 FIG. 48 is a bottom view thereof;
 FIG. 49 is an upper perspective view of a conduit fitting showing our new design in accordance with a seventh embodiment of the present invention;
 FIG. 50 is a lower perspective view thereof;
 FIG. 51 is a left side elevation view thereof;
 FIG. 52 is a right side elevation view thereof;
 FIG. 53 is a front elevation view thereof;
 FIG. 54 is a rear elevation view thereof;
 FIG. 55 is a top view thereof;
 FIG. 56 is a bottom view thereof;
 FIG. 57 is an upper perspective view of a conduit fitting showing our new design in accordance with an eighth embodiment of the present invention;
 FIG. 58 is a lower perspective view thereof;
 FIG. 59 is a left side elevation view thereof;
 FIG. 60 is a right side elevation view thereof;
 FIG. 61 is a front elevation view thereof;
 FIG. 62 is a rear elevation view thereof;
 FIG. 63 is a top view thereof; and,

FIG. 64 is a bottom view thereof.
 The portions of the conduit fitting shown in broken lines form no part of the claimed design.
